UNITED STATES PATENT OFFICE.

CHARLES A. MULLEN, OF SISTERSVILLE, WEST VIRGINIA.

ELECTRIC SPEED OR PRESSURE CONTROL DEVICE.

1,238,066.

Specification of Letters Patent. Patented Aug. 21, 1917.

Application filed October 5, 1916, Serial No. 123,902.

To all whom it may concern:

Be it known that I, CHARLES A. MULLEN, a citizen of the United States, and a resident of Sistersville, in the county of Tyler and State of West Virginia, have invented a new and Improved Electric Speed or Pressure Control Device, of which the following is a full, clear, and exact description.

This invention relates to governors for explosive engines responsive to the pressure of fluid delivered by a pump driven by the engine or to speeds of a moving part driven by the engine, and the invention relates more particularly to an electric device for controlling the ignition circuit of the engine to cause the engine to slow down or stop under predetermined conditions as to pressure or speed.

The invention has for its general objects to provide a device of this character which is of comparatively simple and inexpensive construction, reliable and efficient in use, and so designed that it can be applied as an attachment to pressure, speed or other indicators of that type including a hand or needle movable over a dial.

A more specific object of the invention is the provision of an attachment which is applied to the face of the indicator, whereby an electrical contact coöperates with the needle or hand so that when the latter reaches a predetermined position the electric circuit will be closed to short-circuit the spark plug of the engine.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views,

Figure 1 is a front view of the attachment applied to a pressure gage;

Fig. 2 is a horizontal section of the attachment removed, the section being taken on the line 2—2, Fig. 1; and

Fig. 3 is a diagrammatic view of an ignition system for an explosive engine with the attachment applied.

Referring to the drawings, A designates a pressure gage of the hydraulic type, to which is applied the attachment B. The

gage comprises the usual dial or face 1 disposed within the casing 2, and movable over the dial is the usual hand or indicator 3 connected with the arbor 4, the pressure responsive device for turning the arbor being concealed behind the dial. The casing is connected with a pipe 5, whereby the pressure of the hydraulic medium delivered by the pump connected with the engine is indicated by the gage. The attachment comprises a ring 6 of such diameter as to fit around the casing 2, to which it is clamped by a set-screw 7 passing through the ring. By this means the ring 6 can be adjusted to any desired position around the casing. The usual glass of the gage is removed so as to accommodate a pair of arcuate contacts 7 and 8 carried by the ends of oppositely disposed members 9 and 10, respectively, such members being adjustably clamped to the face of the ring 6 by screws 11. The members 9 and 10 are electrically separated from the ring by insulation 12, as shown in Fig. 2. The outer extremities of the members 9 and 10 have binding posts 13 and 14, respectively, whereby electric wires can be connected therewith. The arcuate contacts 7 and 8 are concentric with the center of the hand 3, and they are spaced apart so that the hand will have a suitable range of movement without engaging with the contacts.

In the diagram shown in Fig. 3 the attachment is shown in connection with a single cylinder engine, there being only one contact employed with the gage A. For a two-cylinder engine, both contacts 7 and 8 will be employed and each will be connected with a spark plug. The cylinder D of the engine has the usual ignition device or spark plug 15 which has one terminal connected with the magneto or source of ignition current 16 by means of the wire 17. Leading from this wire or from the spark plug is another wire 18 which is connected through a switch 19 with the binding post 13 of the contact 7. The contact 7 is insulated from the gage while the needle is connected to ground, as is also one side of the magneto, so that when the needle or hand 3 engages the contact 7, the circuit will be completed by way of the wires 17 and 18, contact 7, hand 3, grounded side of the circuit, and magneto 16. The switch 19 is opened in starting the engine, so that the spark plug will not be short circuited.

While the invention is shown in connec-

tion with a pressure gage it is to be understood that it can be used in connection with a speed gage having a movable hand, whereby the current established can be diverted 5 from the spark plug of the engine under predetermined conditions as to speed.

From the foregoing description taken in connection with the accompanying drawing, the advantages of the construction and 10 method of operation will be readily understood by those skilled in the art to which the invention appertains, and while I have described the principle of operation, together with the device which I now consider 15 to be the best embodiment thereof, I desire to have it understood that the device shown is merely illustrative and that such changes may be made when desired as fall within the scope of the appended claims.

20 Having thus described my invention, I claim as new and desire to secure by Letters Patent:

1. A gage attachment of the class described comprising a ring, means for clamping the ring to the body of a gage, a member insulated from and adjustable diametri-

cally of the ring, said member having its inner ends shaped to form a contact to be engaged by the hand of the gage, and means for adjustably supporting the member on 30 the ring.

2. A gage attachment of the class described comprising a ring, means for clamping the same to the body of a gage, spaced contact members disposed within the ring, 35 and members supporting the contacts and insulating the same from the ring, said members being adjustable toward or from each other to vary the distance between the contacts.

3. The combination of a gage including a casing, a dial, and a hand, with an electric governor attachment therefor comprising a ring clamped to the casing, contacts carried by and insulated from the ring and disposed 40 at opposite sides of the hand for engagement thereby to complete a circuit when the hand reaches one or more predetermined positions, and adjustable means for mounting the contacts to be moved toward or from 45 each other.

CHAS. A. MULLEN.
